UNITED STATES PATENT OFFICE.

ANNETTA MYERS, OF ASHBOURNE, PENNSYLVANIA.

GAME APPARATUS.

SPECIFICATION forming part of Letters Patent No. 503,382, dated August 15, 1893.

Application filed April 19, 1893. Serial No. 471,036. (No model.)

To all whom it may concern:

Be it known that I, ANNETTA MYERS, a citizen of the United States, and a resident of Ashbourne, Montgomery county, Pennsylvania, have invented certain Improvements in Game Apparatus, of which the following is a specification.

The object of my invention is to so construct a game board upon which can be played a game using marbles or balls and a cue, that it will be difficult to make points and in which skill will be required. This object I attain in the following manner reference being had to the accompanying drawings, in which—

15 Figure 1, is a perspective view illustrating my improved game board showing the method of playing. Fig. 2, is a plan view of the board. Fig. 3, is a longitudinal sectional view. Fig. 4, is a sectional view showing the 20 game packed. Fig. 5, is a view showing a single game board; and Fig. 6, is a view illustrating the posts having more than one pocket.

A is the base of the game board in which I prefer to form two grooves *a a*, one at each 25 side for the reception of the marbles or balls with which the game is played. This base is surrounded by a wall B and is of such a height that a cover can be applied thereto and the whole form a box in which the different loose parts of the game can be stored. Preferably in the center of the base is mounted 30 a post D in which is a pocket *d* for the reception of the marbles or balls, this pocket being very little larger than the marble so that it will be difficult to direct the marbles into the pocket. At each side of this central post D are posts E somewhat higher than the post D and the top *e* of each post is depressed 35 as shown in Fig. 3, so that a marble can be placed upon the post as shown in Fig. 1.

The game is played by placing a marble on one of the posts *e* as shown in Fig. 1, and using a cue F and so guiding the cue that it will strike the marble with such force as to 45 direct it into the pocket *d*. The pocket is large enough in the present instance to hold four marbles, but it may be made to hold more than four if necessary and the game may be counted in any manner and the number 50 of marbles used will be regulated according to the rules of playing the game.

I have shown in Fig. 1, a double board having two posts E, but it will be understood

that a single post E may be used as shown in Fig. 5, without departing from my invention 55 and the post D may be duplicated or may have more than one pocket as shown for instance in Fig. 6 and more than two posts E may be used where it is desirable to have more than two players. The main object of 60 the invention being to provide an elevated rest for a marble or ball and an elevated pocket in which the marble is directed.

It will be noticed in playing the game that both hands will have to be elevated and practically unsupported and consequently the 65 player should hold both his hands perfectly steady to insure success.

The several posts are detachable from the base, in the present instance having pins 70 which extend into holes in the base so that on removing the posts they can be packed with the marbles and cues.

I claim as my invention—

1. The combination in a game board, of the 75 base, a post having a pocket therein, with a second post adapted to receive a ball or marble, substantially as described.

2. The combination of the base, with a central post having a pocket in its upper portion 80 adapted to receive a ball or marble, with a post on each side of the central post each side post being recessed at the top to receive a marble, substantially as described.

3. The combination of the base A, the side 85 walls B, grooves on each side of the base for the reception of marbles, a central post D having a pocket *d* and a side post or posts recessed at the top upon which the marble can be mounted, substantially as described. 90

4. The combination of the base having side walls, the detachable central post having a pocket, with detachable side post or posts upon which a marble may be mounted in playing the game, substantially as described. 95

5. The combination of the base, the post E upon which a marble is mounted, with a post D having a central upper pocket and one or more side pockets, substantially as described.

In testimony whereof I have signed my 100 name to this specification in the presence of two subscribing witnesses.

ANNETTA MYERS.
